UNITED STATES PATENT OFFICE.

TORRENCE V. CALDWELL, OF DU BOIS, PENNSYLVANIA.

VALVE-GRINDING MACHINE.

Application filed December 17, 1927. Serial No. 240,759.

- This invention relates to a machine for grinding the elements of triple valves employed in air brake systems, and it has for an object the provision of novel means for expeditiously and uniformly grinding the contacting surfaces of the coacting members in a manner to insure proper seating of the valve and the restoration of the valve to efficient condition.
- 10 It is a further object of this invention to provide novel means whereby the slide valve may be operated or moved in engagement with its seat, means being provided for exerting pressure or force on the parts while they are in motion to insure uniformity of operation. Means are also provided in association with the slide valve grinder for lapping in a graduating valve and the mechanisms are driven from the same source of power.
- 15 It is a still further object of this invention to produce a valve grinding machine in which the parts of the valve to be utilized during the grinding operation may be expeditiously applied or removed from the machine.
- 20 With the foregoing and other objects in view, the invention consists in the details of construction, and in the arrangement and combination of parts to be hereinafter more fully set forth and claimed.
- 25 In describing the invention in detail, reference will be had to the accompanying drawings forming part of this application, wherein like characters denote corresponding parts in the several views, and in which—
- 30 Figure 1 illustrates a view in elevation of a grinding machine embodying the invention;
- 35 Figure 2 illustrates a view in elevation of one end of the machine;
- 40 Figure 3 illustrates a plan view of said machine, duplicated parts being omitted.
- 45 Figure 4 illustrates a detail view of one of the guide members; and
- 50 Figure 5 illustrates a detail view of another guide member.

In these drawings, 10 denotes a suitable bed plate which is preferably provided with mechanism for grinding two slide valves and two graduating valves, but, as the mechanism for grinding a slide valve and the mechanism for grinding a graduating valve are duplicated, a description of the mechanism for grinding one of the slide valves and one of the graduating valves will, it is thought, be

sufficient to enable one skilled in the art to practice the invention.

As here shown, the base is provided with bearing brackets or posts 11 in which a power driven shaft 12 is journaled. The pulley 13 on the shaft 12 may be driven from any suitable source of power, and the inventor does not wish to be limited, of course, with respect to this detail. Wheels 14 and 15 are carried on the shaft near its ends and each wheel has a wrist pin, such as 16, on which a pitman 17 is mounted, and each of the said pitmen is intended to be pivotally connected to a thrust rod or bar 18 which is to be reciprocated preferably in a horizontal plane above the bed plate. Each rod 18 is provided with an aperture 19 to receive a pin 20 by which the slide valve of a triple valve is connected to the rod 18 in order that the slide valve 21 may be reciprocated on its bushing when a triple valve casing 22 is attached to the base. It is understood, of course, that each pitman will reciprocate a rod 18 associated with the triple valve casing and parts to be lapped. Each rod 18 is maintained in operative relation to the valve by the sectional guides, one of which is located at each end of the valve casing.

Each guide, in the present embodiment of the invention, comprises a post 23 rising from the bed plate and being provided with a bolt 24 slidable in a slot 25 of said post 23. The section 26 of the post also has a slot 27 coinciding with the slot 25 of the post 23, and the slot 27 receives the bolt 24 to permit an adjustment of the guiding member 26 vertically and when proper adjustment has been attained, the parts will be secured together by the bolt.

In order to insure proper pressure of the slide valve on the bushing while the rod is reciprocating, a spring 28 is connected to the said rod and to an anchor 29 on the base in front of the location of the valve casing, and a spring 30 is connected to the said rod and to an anchor 31 on the base at the rear of the location of the valve casing and it is the purpose of the inventor that these springs shall yieldingly hold the valve on its bushing while it is being reciprocated and that the strength of the springs shall be such that the friction of the valve will be augmented to a degree to facilitate the valve lapping operation.

It is shown in the drawing that the base is

provided with an annular shoulder 32 which forms a seat for the valve, and the base at locations near the flange has threaded apertures 33 which receive anchors by which the 5 flange of a valve may be secured to the base to hold the valve casing rigid.

When a slide valve is to be lapped, the triple piston of a triple valve is removed from the valve casing by removing the pin which 10 connects the slide valve to the triple piston and when the piston has been removed, the rod 18 is inserted in the valve casing and the pin 20 corresponding to the pin which holds the slide valve to the triple piston is employed 15 for connecting the reciprocating rod to the slide valve, after which power is applied to drive the grinding machine and the slide valve is reciprocated on its bushing until a leak-proof joint has been formed between the 20 said slide valve and its bushing, after which, of course, the triple valve may be reassembled.

In addition to the mechanism just described, the machine embodies elements which 25 may be employed for grinding the graduating valve. In this additional provision, journal bearings 34 and 35 are located between the posts or bearings 11 and a shaft 36 is journaled in the bearings 34 and 35. A pulley 37 on the shaft 12 and a pulley 38 on the shaft 30 36 may be connected by a belt 39 in order that the shaft 36 will be driven when the shaft 12 is rotated. Wheels or disks 40 near the ends of the shaft 36 have wrist pins 41 on which pitmen 42 are mounted and these pitmen are 35 pivotally connected to reciprocating rods 43 that operate in guides, such as 44, across the supplemental bed plate 45 which is intended to hold the slide valve while lapping in the graduating valve, it being stated that the rod 40 43 is provided with a clip 46 which holds the graduating valve. The operation attending the lapping of the graduating valve is practically the same as that for lapping the slide valve, and the reciprocating rod 43 is under

tension of a spring 47 which is connected to 45 the said rod and suitably anchored to the base. A recess 48 is formed in the supplemental bed plate 45 to receive the slide valve, and the recess 49 in the supplemental bed plate for the slide valve is different in size 50 from that of the recess 48.

I claim:

1. In a valve grinding machine, a bed plate having a seat for a valve case, a rod adapted to be reciprocated above said seat, said rod 55 having an aperture to receive the pin of a slide valve whereby the slide valve is connected to move with the said rod, an adjustable guide at the front and rear of said seat, each of said guides comprising a post having 60 a coacting section adjustable vertically, means for holding the parts in adjusted positions, a spring connected to said rod in front of the seat of the valve case, a spring connected to said rod at the rear of the valve case, means 65 for anchoring each of the said springs, and means for reciprocating the rod.

2. In a valve grinding machine, a bed plate having a seat for a valve case, a rod adapted to be reciprocated above said seat, said rod 70 having an aperture to receive the pin of a slide valve whereby the slide valve is connected to move with the said rod, an adjustable guide at the front and rear of said seat, each of said guides comprising a post having a coacting 75 section adjustable vertically, means for holding the parts in adjusted position, means for exerting tension on the rod, means for reciprocating the said rod, a supplemental bed having seats, elements guided approximately 80 horizontally above said seats, means for reciprocating said elements, clips carried by said elements for engaging valve elements for moving said valve elements with respect to other elements seated on the supplemental bed plate, and means for exerting tension 85 downwardly on said elements.

TORRENCE V. CALDWELL.
